UNITED STATES PATENT OFFICE.

HERBERT G. BEEDE, OF PAWTUCKET, RHODE ISLAND.

RING SPINNING OR TWISTING DEVICE.

1,174,961.

Specification of Letters Patent. Patented Mar. 14, 1916.

Application filed April 17, 1915. Serial No. 22,101.

To all whom it may concern:

Be it known that I, HERBERT G. BEEDE, a citizen of the United States, residing at Pawtucket, in the county of Providence and State of Rhode Island, have invented certain new and useful Improvements in Ring Spinning or Twisting Devices, of which the following is a specification.

This invention relates to the construction of rotary traveler-rings employed in connection with ring-spinning or twisting, and it consists essentially in certain novel features hereinafter set forth and claimed.

In United States patents numbered 1,075,004 and 1,075,185, issued to me on the 7th day of October, 1913, I have claimed other improvements in apparatus of the general type or character referred to. In the construction of former devices of this type rotary ring members were mounted to slide on surfaces of the stationary fellow members, thus materially increasing the normal resistance or work when initially starting to wind the yarn on the spool.

In the present device the construction is such that in starting the rotation of the spool the amount of working friction is materially reduced, and so that when the spool has attained its normal speed the centrifugal force of the rotating members acts to retard the traveler-ring, thus providing the latter with a substantially uniform normal dragging or lagging effect and automatically imparting to the yarn a proper tension and twist while the load is being wound upon the spool.

The essential object of this invention is to provide a rotary traveler-ring that in starting will move more easily and with less frictional resistance than other analogous devices heretofore produced.

In the accompanying drawing Figure 1 represents a top plan view of my improved traveler-ring device, the ring having a plurality of independently revoluble rolls bearing on a relatively stationary base-ring, portions of the rings being broken away to show the interior construction; Fig. 2 is a corresponding side elevation, also in partial section; and Fig. 3 is an enlarged cross-section, taken on line 3-3 of Fig. 2. Broken lines in Figs. 1 and 2 indicate the

relation of the spool and the yarn being acted upon.

In my improved device A indicates an annular non-revoluble base-ring having what may be termed lower and upper inner flanges a , a^1 , said flanges being bored to receive a positively driven spool T, indicated by broken lines. The member A is also provided with an upwardly extending outer rim a^2 disposed concentric to and integral with the said other flanges and at right angles to the base flange a^2 and annular recess whose face a^4 constitutes a track for supporting the rolls D. The said surfaces a^6 and a^4 are adapted to be engaged by the rolls D of the balanced traveler-ring B, later described. To the rim a^2 is removably secured, by screws f , an annular protector-guard or cap-ring C for maintaining the traveler-ring and its members in the normal position and relation. The device may be mounted in a ring-tail t . See Fig. 2. The underside of member C may be engaged by the rolls D.

An inner flange b^1 of the traveler-ring member B conforms to and freely rotates relatively to said stationary flange a^1 . See Fig. 3. The downwardly extending outer flange b of ring B is provided with a series of uniformly spaced radial axles or pins d accurately mounted therein. The axes of the pins d are fixed at right angles to the center or longitudinal axes of the concentric main members A and B. Each pin or axle is adapted to receive and revolvably support a roll D of steel or other wear-resisting material.

The roll-units are accurately turned and bored so as to rotate true on the pins and track a^4 . The ends of the rolls may be made convex or slightly spherical, described from a radius equal to the semi-diameter of the vertical annular surface a^6 . The rolls may be interchangeable and reversible by simply making both ends alike in convexity. A slight play or clearance is provided between the ends of the rolls and the adjacent circular surface a^6 , as indicated at s , and an even greater clearance may be provided between the adjacent surfaces of the flanges a^1 and b , substantially as shown at s^1 , Fig. 3.

To the upper face of the ring B is secured

a pair of oppositely positioned eyes or thread-guides E; each eye, as represented, consisting of a porcelain or other suitable annular member e having well-rounded ends 5 and a central opening e^1 . Said guides are fixed to the ring by means of straps e^2 and screws e^3 .

By means of my improvement the rolls D, which may be termed tension-rolls, move 10 around bodily with the traveler-ring, while at the same time the rolls in engagement with the stationary circular track a^4 are adapted to turn independently on their axles d . The rolls may move freely endwise 15 or outwardly through centrifugal action, thereby causing them to engage frictionally with the vertical surface a^5 of the base-ring A, and producing a lagging or retarding effect on the traveler-ring and yarn. 20 The said tension or drag, it may be observed, is due to variations in the speeds of rotation of the spool and the traveler-ring, and the centrifugal force of the rolls of the latter.

25 In the present device it is apparent that the construction is such that at the instant of starting the traveler-ring its members D are adapted to roll on the surfaces of the stationary member A, thus materially reducing 30 the amount of working friction through the employment of rolling friction. When the traveler-ring has attained its normal speed the centrifugal action of members D causes the latter to frictionally engage the 35 corresponding surfaces of the stationary fellow member, thus producing automatically a suitable lagging or dragging effect to the traveler-ring, which in turn imparts a proper tension to the yarn t^1 as it is wound 40 on the revolving spool T. The maximum diameter of the spool-load is indicated at t .

In order to reduce the drag on the yarn leading from the feed-rolls to the guide-eye of the traveler-ring certain of the 45 mounted rolls may be omitted from the corresponding axles at diametrically opposite points, the resulting effect being to lessen the weight and centrifugal action, assuming the other conditions to remain unchanged, thereby producing a spool having 50 a correspondingly lighter yarn tension. Obviously, a contrary tension effect may be produced upon the yarn by increasing the number of the rolls. In any event, however, 55 the ring B, including its axles and rolls, should be revolvably balanced.

The device is capable of being lubricated by means of a grease-cup connected with a

duct o formed in the ring-rail and communicating with opening o^1 formed in the 60 base of the track recess.

I claim as my invention:—

1. In a ring-spinning or twisting device, the combination with a stationary base-ring provided with an annular track, of a rev- 65 oluble traveler-ring on said base-ring, a plurality of peripherally spaced axles fixed to and projecting radially outward from the traveler-ring, and movable bodily with it, and anti-friction rolls freely revoluble on 70 said axles, said rolls being in frictional engagement with the annular track of the base-ring and supporting the traveler-ring.

2. In a ring-spinning or twisting device, the combination of a stationary base-ring having 75 an axial opening for the passage of a winding spool, a rotary traveler-ring having its axis of rotation alining with the axis of the base-ring, a thread-guide carried by the traveler-ring, a plurality of peripherally 80 spaced pins or axles, said axles being fixed to and extending radially outward from the rotary ring, and independently movable tension devices mounted for rotation on said 85 axles and being in normal engagement with the base-ring, the axes of the axles being arranged at right angles to the axes of the said base and traveler-rings.

3. In a ring-spinning or twisting device, the combination with a stationary base-ring 90 having a flat, circular track, of a traveler-ring revoluble on said base-ring, and a plurality of rolls, mounted for independent rotation, carried by the traveler-ring, the said rolls being in frictional engagement 95 with said track of the base-ring, for the purpose set forth.

4. In a ring-spinning or twisting device, the combination with a stationary base-ring having a pair of circular tracks arranged at 100 substantially right angles to each other to form vertical and horizontal surfaces, respectively, of a traveler-ring revoluble on said base-ring, and a plurality of removably mounted rolls movably connected with the 105 traveler-ring and revoluble bodily therewith, said rolls arranged to be moved by centrifugal action to engage the said vertical surface of the stationary ring.

In testimony whereof I have affixed my 110 signature in presence of two witnesses.

HERBERT G. BEEDE.
